FLOOR SCRUBBER OR THE LIKE

Alvin B. Baranov, West Hollywood, Frank C. Houser,
Granada Hills, and Richard E. Larson, Los Angeles, Calif.

Application August 19, 1957, Serial No. 47,445

Term of patent 7 years

(Cl. D9—2)

The dominant features of our design reside in the portions shown in solid lines.

We claim:

The ornamental design for a floor scrubber or the like, substantially as shown and described.
